UNITED STATES PATENT OFFICE.

DAVID WILLIAMS OGILVIE, OF BALBOA, CANAL ZONE.

PARACHUTE APPARATUS.

1,110,711.

Specification of Letters Patent. Patented Sept. 15, 1914.

Application filed March 18, 1913. Serial No. 754,153.

To all whom it may concern:

Be it known that I, DAVID W. OGILVIE, a subject of the King of England, residing at Balboa, Canal Zone, have invented certain new and useful Improvements in Parachute Apparatus, of which the following is a specification, reference being had to the accompanying drawings.

This invention comprehends certain new and useful improvements in parachute apparatus and has for its primary object to provide a device of this character which will be of extremely simple construction and operation and which will serve to prevent an airship from descending suddenly to the earth.

Another object is to provide a device of this character which may be readily operated should the engine stop or get out of order, the device serving to arrest the sudden descent of the machine and cause the latter to descend slowly, thereby preventing injury to the machine and the occupants thereof.

A further object is to provide a device of this character which will include a bell and parachute secured above the same and normally inclosed with the bell in a gun barrel to be ejected from the upper end of the latter upon operation of the gun, thereby permitting the parachute to open and serve to anchor the airship in mid air and then allow gradual descent of said airship.

A still further object is to provide a device of this character which may be positioned adjacent the operator of the airship and in which compressed air may be employed for ejecting the parachute carrying bell and parachute.

With the above and other objects in view, my invention consists in certain novel constructions, combinations, and arrangements of parts to be hereinafter more fully described, claimed, and illustrated in the accompanying drawings, in which,

Figure 1 is an elevational view partly in section, showing the device in inoperative position; and Fig. 2 is a view similar to Fig. 1, showing the device after the bell and parachute have been ejected from the upper end of the barrel.

Referring more specifically to the drawings in which similar reference characters designate corresponding parts throughout the several views, A designates the barrel which has its upper end open while its lower

end is closed and which decreases gradually in diameter toward its upper end, as clearly shown in the drawing. The barrel is divided into the lower compartments *a* and *b* and upper compartment *c*, the purpose of which will presently appear.

Within the lower compartment *a* is the transverse shaft F positioned adjacent the bottom of the barrel and extending beneath the lower compartment *b*. The shaft has a drum f mounted thereon with the cord f wound thereon and one end of the shaft projects through the side of the drum and has the crank arm f' mounted thereon, by means of which the shaft F may be readily rotated with the drum f to wind the cord f upon said drum. The cord f' is also secured to the fastening member g engaged through the center of the bell h, it being understood that said cord f' is secured to the end of the fastening member g within the bell h.

The bell h normally rests upon the upper flat wall i of the lower compartments *a* and *b* and has the substantially U-shaped frame member h' secured to its upper convex face by the fastening member j, the shaft k being mounted in the upper extremities of the upstanding legs of said substantially U-shaped frame member h' with the drum j mounted thereon between said legs. One end of the shaft k has a right angled arm k' secured thereon, to which is hinged the handle k'' which is adapted, when not in use, to be folded against the arm k' to avoid the edge of the barrel, as will be readily understood.

The drum j has the cord j' secured thereto and adapted to be normally wound upon the same, said cord j' being a continuation of the separate cords n' secured to the edge of the parachute n, the separate cords n' being secured together, as shown at m, and a plurality of rings l of cork or other suitable material being engaged around the cords j' immediately below the point m. When the bell h is in normal position and the cord j' is wound upon the drum j, the parachute n is in collapsed condition, and, together with the rings l, rests upon the drum j, all of these parts being within the upper compartment *c* of the barrel A.

It will be understood that the upper wall i of the lower compartments *b* and *c* has an air escape opening i' over the compartment *b*, the purpose of which will presently ap-

pear. It will also be understood that the upper wall *i* has a suitable slot provided therein over the compartment *a*, through which the cord *f*' extends, and it will further be understood that the vertical wall *b*', dividing the compartments *a* and *b*, may be secured to the wall *i* in any suitable manner. The bottom wall and intermediate guide partition of the compartment *b* are formed by the legs of the U-shaped member *b*'' which has the opposite ends of its legs secured to the vertical wall *b*' while the central or bight portion of said member is outwardly of the side wall of the barrel and forms a guard for the trigger *d*.

The free end of the trigger *d* is inclosed within the central or bight portion of the U-shaped member *b*'' and said trigger extends through a slot *a*' in the outer wall of the barrel and extends toward the plunger rod *e*. The trigger is then bent back upon itself, thereby forming the nose *d*' for engagement in the notch *e*' in the plunger rod *e*, to retain the latter and the plunger *e*'' upon the upper end of said plunger rod, in their lowermost positions with the spring *e*''' compressed around the plunger rod *e*. After forming the nose *d*', the trigger is extended downwardly and then curved outwardly toward the outer wall of the barrel *A*, and secured to the bottom wall of the compartment *b*, as shown at *d*''.

From the foregoing, it will be clearly apparent that should the engine of the airship stop, or should any part of the airship get out of order, the operator may readily press the outer end of the trigger *d* and thereby disengage the nose *d*' of said trigger from the notch *e*' in the plunger rod *e* and allow said plunger rod *e* and plunger *e*'' to be forced upwardly by the spring *e*''' to compress the air above the same and force said air against the bell *h* to eject the latter, together with the parachute *n* and parts between said bell and parachute, from the upper open end of the barrel *A*. It will also be understood that the cord *f*' is of sufficient length to allow a quantity of the same to be loosely positioned in the compartment *a*, thereby making it unnecessary for the drum *f* to rotate to feed out the cord *f*' wound upon the same, until after the parachute *n* and bell *h* have been ejected from the barrel *A*, after which the parachute will open and the cord *f*' unwind from the drum *f* and the cord *j*' unwind from the drum *j*. As soon as the cords *f*' and *j*' unwind from their respective drums, downward movement of the airship will be arrested and controlled by the parachute *n*, thereby causing a slow and steady descent of the airship to the ground.

While I have shown the preferred embodiment of my invention, it will be under-

stood that minor changes in the details of construction and arrangement of parts may be made within the scope of the appended claims, without departing from the spirit of my invention or sacrificing any of the advantages of the same.

What is claimed is:—

1. A device of the class described comprising a barrel including an upper compartment, and a lower compartment, a bell within the upper compartment, a parachute connected with the bell, said upper and lower compartments being separated by a transverse partition having an opening therein, means within the lower compartment for forcing air therefrom to eject the bell and parachute from the barrel, means for limiting outward movement of the bell, and means for locking against operation the means within the lower compartment.

2. A device of the class described comprising a barrel having a transverse partition and an open upper end, the lower portion of the barrel being divided into two compartments, a piston within one compartment, the transverse partition above said compartment being provided with an air escape opening, a bell within the upper compartment and engaged over said opening in the transverse partition, a parachute carried by said bell, a trigger within said lower compartment and having one end secured to the lower wall of the latter, the opposite end of said trigger projecting through the wall of the barrel, said trigger having a nose intermediate its ends and normally engaged with the piston to retain the same in its lowermost position, means for forcing the piston upwardly to compress the air beneath the bell and eject the same with the parachute from the barrel upon disengagement of the nose of the trigger with said piston, and means for limiting outward movement of the bell.

3. A device of the character described comprising a barrel, a bell within the barrel, a parachute connected to said bell, pneumatic means for ejecting the bell and parachute from within the barrel, and means for limiting the outward movement of the bell, such means also serving to return the bell within the barrel.

4. A device of the character described comprising a barrel, a bell insertible within the barrel, a rotatable drum carried by the bell, a parachute, a flexible connection between the parachute and drum, and means for ejecting the bell from within the barrel.
